UNITED STATES PATENT OFFICE.

HENRY G. LEWIS AND WALTER S. MAYER, OF PHILADELPHIA, PENNSYLVANIA,
ASSIGNORS, BY DIRECT AND MESNE ASSIGNMENTS, TO SAID MAYER.

GRADOMETER.

1,378,042.

Specification of Letters Patent. Patented May 17, 1921.

Application filed October 22, 1919. Serial No. 332,457.

To all whom it may concern:

Be it known that we, HENRY G. LEWIS and WALTER S. MAYER, citizens of the United States, and residents of the city of Philadelphia, in the county of Philadelphia and State of Pennsylvania, have jointly invented certain new and useful Improvements in Gradometers, of which the following is a specification.

10 This invention relates to improved means adapted for indicating grades generally but is designed primarily for application to motor vehicles, as to the cowl or dash, for the purpose of indicating the roadway gradient 15 upon which the vehicle is standing or moving.

The chief object of the invention is to provide an improved construction that is simple, efficient, durable, self-contained, 20 readily applied and readily adjusted to different positions of use.

The characteristic features of the invention are disclosed in the forms thereof set out in the following description and the 25 accompanying drawings in illustration thereof.

In the drawings, Figure 1 is a front elevation of a form of our improved device; Fig. 2 is a part sectional side view of the 30 same; Fig. 3 is a sectional view taken on the line 3^x-3^x of Fig. 2; Fig. 4 is a front elevation of a second form of the device, and Fig. 5 is a sectional view taken on the line 5^x-5^x of Fig. 4.

35 The invention, in the form shown in Figs. 1 to 3 inclusive, comprises a rim 1 having a peripheral flange 1', a curved shell 2 having a peripheral flange 2' and a spheroidal dial 3 having a central slot 4 with scales 40 4' at the sides thereof and having a peripheral flange 3' clamped between the flanges 1' and 2', the dial being covered by a glass 5 carried by the rim. The shell is designed to be set in an automobile cowl or dash with 45 the connected flanges engaged thereto.

An arbor 6 is supported in the shell 2, transversely to the slot 4, by the studs 7 and 8 set in opposite sides thereof, and a toothed weight 9, preferably symmetrical 50 with reference to a transverse axis, is journaled eccentrically on the arbor, the weight having a serrated hub 10 fixed thereto concentrically with the arbor, and acting in an oil bath for damping its oscillations.

55 A lever 11 is mounted loosely on the ar-

bor 6, adjacent to the hub 10, and has a member 11' extending laterally therefrom across the hub. A bolt or shaft 12, in the plane of the slot 4, extends through the member 11', is provided at its outer end 60 with a double indicator or hand 12' adapted to move over the scales 4', and has at its inner end the shouldered tooth 12'' adapted to engage the serrations of the hub 10 in normal relation thereto. The tooth 12'' is 65 held in engagement with the hub 10 by a spring 13 on the bolt 12, the spring bearing against the parts 11' and 12''.

The device is set, for accommodation to the different angles between the horizontal 70 and the vertical which it (the plane of its flange 3') may occupy on a car that is on a level way, by drawing out the bolt 12 so as to disengage the tooth 12'' from the hub 10, setting the pointer 12' at zero on the 75 scales 4', permitting the weight 9 to assume its normal position and reengaging the tooth with the hub, where it is held by the spring 13.

When the car, with the device thus set, 80 stands or moves on a grade, the gradient will be indicated by the action of the weight 9 through the hub 10 on the bolt 12 which sets the pointer 12' at the side of the zero 85 marks on the scales 4' and at the position indicating the degree or percentage of the ascending or descending grade, as the case may be.

In the form of the device illustrated in 90 Figs. 4 and 5, the rim 16 and the shell 17 have a dial 18 clamped between them, the rim being provided with a glass 19. The arbor 20, carried by studs 21 and 22 set in the shell 17, has journaled eccentrically 95 thereon the toothed disk 23 acting in a bath of oil and providing a weight symmetrical with reference to a transverse axis and which has fixed thereto concentrically with the arbor 20 a beveled gear 24, the disk acting in oil contained in the shell to damp 100 its action.

A beveled pinion 25 is fixed on a shaft 26, which is journaled in the dial 18, and engages the beveled gear 24. The shaft 26 has thereon a hand 27 which is movable 105 over the circular scale 18' of the dial 18.

When a car with this device mounted thereon is on a level way the hand 27 will be set to stand at zero on the scale 18', and when on an up or down grade, such hand will 110

stand on the side of the zero point and at the position indicating the grade, whether up or down.

This device is also adapted for use with 5 the dial 18 at any position between the horizontal and the vertical when the car is level, by setting the gear 25 on the shaft 26 so that the hand 27 will stand at the zero position on the scale or by setting the hand 10 relatively to the shaft, the weight 23 being in its normal position.

This mechanism, employing a symmetrical weight journaled by means of an arbor not greatly removed from its center of gravity, is sensitive without being unstable in 15 operation.

Having described our invention, we claim:

1. A gradometer comprising a rim provided with a flange, a shell provided with a 20 flange, a dial clamped between said flanges, an arbor supported in said shell, an oscillatory weight mounted eccentrically on said arbor in said shell, a pointer movable over said dial and means whereby the movement 25 of said weight about its axis moves said pointer proportionately over said dial.

2. A gradometer comprising a shell containing a liquid, an arbor having a horizontal axis journaled in said shell, a weight 30 fixed eccentrically to said arbor and movable in said liquid, and an indicating device fixed to said arbor and movable in a vertical arc by said weight.

3. A gradometer comprising a shell containing a liquid, an arbor in said shell, a symmetrical weight, journaled eccentrically by means of said arbor, an indicating device 35 movable in a vertical arc by means of said weight acting through said arbor, and 40 means for adjusting the relation of said indicating device to said weight and arbor.

4. A gradometer comprising a shell provided with a liquid bath, an arbor supported in said shell, a weight journaled eccentrically by means of said arbor so as to 45 oscillate in said bath, teeth fixed to said weight concentrically to said arbor, a shaft, a pointer fixed to said shaft, a dial fixed to

said shell and means connected adjustably in relation to said teeth and operated thereby to operate said shaft and move said pointer in a circular arc over said dial.

5. A gradometer comprising a weight having a substantially horizontal axis of oscillation removed from its center of gravity, means for damping the oscillations of said weight, a shaft disposed transversely to said axis, and connected to said weight so as to oscillate in a substantially vertical plane, an indicating device carried by said 55 shaft, and a dial over which said device is movable by said shaft.

6. A gradometer comprising a weight having an axis of oscillation removed from its center of gravity, a toothed hub fixed to 60 said weight, a spring pressed bolt connected normally in adjustable relation to said hub, a pointer carried by said bolt and a dial over which said pointer is movable.

7. A gradometer comprising a shell, a 70 dial provided with a slot fixed to said shell, an arbor fixed in said shell transversely to said slot, an oscillatory weight mounted eccentrically on said arbor, a serrated hub fixed to said weight concentrically to said 75 arbor, a spring pressed bolt connected normally in adjustable relation to said hub and adapted to oscillate in said slot, and an indicator carried by said bolt and movable thereby over said dial.

8. A gradometer comprising a shell, a dial fixed to said shell, an arbor fixed in said shell, an oscillatory weight mounted eccentrically on said arbor, an angle lever mounted on said arbor, and movable about 85 the axis of oscillation of said weight, a serrated hub fixed to said weight concentrically with its axis of oscillation, a spring pressed bolt supported by said lever in adjustable relation to said hub, and a pointer 90 carried and movable by said bolt over said dial.

In testimony whereof we have hereunto set our names this 20th day of October, 1919.

HENRY G. LEWIS.
WALTER S. MAYER.
